CONRAD SCHICKERLING, OF EAST ORANGE, NEW JERSEY, ASSIGNOR OF ONE-HALF TO
LILLIE E. SCHICKERLING AND HORTENSE SCHICKERLING, BOTH OF EAST ORANGE,
NEW JERSEY.

RADIOTUBE.

Application filed February 6, 1925. Serial No. 7,225.

This invention relates to radio equipment and has particular reference to the novel and peculiar construction of amplifying and detection tubes or the like.

Among the objects of the invention is to provide a radio tube having peculiar properties for the elimination of all static, roaring, whistling, clattering, and all other types or species of interferences or external disturbing noises.

A further object of the invention, more specifically stated, is to provide a radio tube having a fourth element, a stabilizer, in addition to the usual or well-known filament, grid, and plate elements sealed within a vacuum tube or bulb.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a face view of a preferred embodiment of my improvement, parts being in section.

Fig. 2 is a fragmentary view of the interior parts taken substantially at a right angle to the view of Fig. 1 and with parts broken away.

Fig. 3 is a cross section on the line 3—3 of Fig. 1.

Fig. 4 is an elevation of my improvement embodied in a modified form of construction.

Referring now more specifically to the drawings I indicate a radio tube comprising a bulb 10 cemented as usual into a base 11 carrying the conventional four contact studs, 12 and 13 for the filament, 14 for the grid, and 15 for the plate. 16 is the pedestal for supporting the interior fittings and through which the several wires lead to the contact studs in the usual manner.

At 17 I indicate a suitable filament leading from one support 18 to another 19. The mid portion of the filament is supported upon a post 20 secured in the pedestal. The supports 18 and 19 are attached to filament wires

12^a and 13^a which lead to the corresponding studs 12 and 13.

A suitable form of grid is shown at 21 which in Figs. 1 and 2 is composed of upper and lower spaced parallel bars 22 between which are stretched a series of fine wires 23. The filament 17 is held in position spaced from the wires 23 and preferably between the two series thereof. The grid as just described is supported at one end upon a dummy post 24 and at the other upon a connection from which a wire 26 leads to the stud 14.

In this form of the invention the plate element consists of a metal plate 27 looped in spaced relation over and on the sides of the grid and filament, the lower edge portions of the plate being connected to and supported by a plate post 28 and a support 29 from which leads the wire 30 to the contact stud 15.

The novel and added element constituting the principal feature of this improvement, is known as a stabilizer and while it may be exemplified and practised in many different forms or embodiments, it is shown in Figs. 1 and 2 as consisting of a composite plate structure 31 of polygonal form but having an open center 32 through which extends the plate and other elements just described in a direction substantially perpendicular to the general plane of the stabilizer and spaced therefrom. This element is shown as embodying a plurality of flared wings 31^a spaced from each other and from the top of the plate 27. The stabilizer, however, comprises two legs 33 on opposite sides and spaced from the sides of the plate 27, one of these legs being provided with a supporting post 34 and the other has a supporting member 35 from which leads a wire 36 through the pedestal 16, this wire being united as by twisting with one of the filament wires and so is attached thereby to one of the filament studs. While I indicate this connection with the wire 13^a and stud 13, the connection might be made with the other filament wire.

The modification shown in Fig. 4 is what I term a power tube arrangement or construction, the same being adapted for more powerful amplification or detection, but like in the first form, with a remarkably low amperage in proportion to the amplification

and efficiency realized. In this form the bulb 10^a is shown mounted upon or within a base 11 and provided with the standard fittings, the contact studs 12 to 15, the pedestal 16, and the usual three elements as identified in the foregoing description. The filament 17^a is of the form in which a simple wire is supported or suspended between two supports 18^a and 19^a from which the wires 10 12^a and 13^a respectively extend to the studs 12 and 13. This filament 17^a is stretched through the central space within a grid 21^a in the form of a coil supported upon two supports 24 and 25, from the latter of which 15 leads a wire 26 to the contact stud 14. The plate 27^a is supported by means of two supports 28 and 29, from the latter of which leads a wire 30 to the stud 15.

The stabilizer 31^b in this form is shown as 20 comprising three wings 31^c flared away from one another and surrounding the plate 27^a as by means of openings 32^a. This stabilizer as in the previous form is supported by a support 35 from which leads a wire 36 united 25 as by twisting with the filament wire 13^a as above described.

As a result of extensive experiments and practice of this invention in various designs and forms I have established the fact that 30 because of the fourth element or stabilizer it is possible to secure remarkable freedom from tube noises so commonly experienced

with other tubes, but the scientific reason for the effect I am not at this time able to explain.

35

I claim:

1. In a radio tube, the combination with filament, grid, and plate elements, of a fourth stabilizing element to eliminate objectionable tube noises, the stabilizing element being a 40 plate disposed centrally and at right angles to the first mentioned plate, and having electrical connection with the filament.

2. In a radio tube, the combination with filament, grid, and plate elements, of a fourth 45 stabilizing element to eliminate objectionable tube noises, the stabilizing element comprising a plate having an opening and through which the first mentioned plate extends in spaced relation in a direction substantially 50 perpendicular to the plane of the stabilizer plate, said stabilizer plate having electrical connection with said filament.

3. In a radio tube, the combination with filament, grid, and plate elements, of a fourth stabilizing element to eliminate objectionable tube noises, the stabilizing element comprising a plate having an opening through which the first mentioned plate extends in a direction substantially perpendicular to the plane of the stabilizer plate.

In testimony whereof I affix my signature.

CONRAD SCHICKERLING.
